(57) **CLAIM**

A design for a drying device, as shown and described.

DESCRIPTION

FIG. 1 is a slightly reduced perspective view of the drying device showing my new design;

FIG. 2 is a top plan view thereof; and,

FIG. 3 is a side elevational view thereof.

The design consists of the features of shape and configuration shown in solid lines in the drawings. The stippled lines in FIGS. 1 and 4 show environment and do not form part of the design.

The broken lines shown on the drying device are included for the purpose of illustrating a portion of the drying device that forms no part of the claimed design.
